Claims priority, application Czechoslovakia Mar. 6, 1951 10

3 Claims. (Cl. 313—186)

This invention relates to tactitrons, that is, gaseous discharge tubes of the kind having at least one anode and a control grid arranged in the positive column of discharge or in the area of anode potential drop, for discontinuous control, and particularly for interruption of the current by means of a comparatively small negative grid bias even in the case of maximum anode current. The interruption of the current is caused by the so called Langmuir layer, that is, a layer of positive ions which surround the negatively charged electrode in the plasma or ionized area where there is an equal number of positive and negative particles so that the electrode appears to be neutral. The effective transparency of the grid is diminished by these layers of positive ions and the thickness of such layers depends, in turn, on the negative charge of the electrode with reference to the potential of the plasma, on the pressure of the gas filling the discharge tube, on the degree of ionization of this gas, and on the nature of the discharge. If the transparency of the grid is diminished below a certain level, an interruption or cutoff of the discharge is effected.

According to the theory known so far, see, for example, Johnson, Olmstead, Webster "The Tacitron . . ." Proc. of the IRE, September 1954, pp. 1350—1362, the effective transparency of the grid is given by the expression

$$\phi_e = \frac{(1-nd)^2}{\left(1 + \frac{nd}{10}\sqrt{U}\right)^2}$$

where

$$U = \frac{V_g^{3/2} \cdot \sqrt{\frac{M \cdot T_e}{m \cdot T_p}}}{\frac{d}{2} \cdot i}$$

the notation being:

n—number of grid openings per cm.,
d—grid wire diameter,
V_g—negative grid bias,
i—electron current density on the anode surface,
M—ion mass,
m—electron mass,
T_e—electron temperature,
T_i—ion temperature.

It is evident from this expression, that the smaller the grid openings, the larger the percentage reduction of the grid transparency with otherwise the same thickness of the Langmuir layers. Therefore, if it is desired to achieve an interruption of the discharge by the grid bias, it is necessary to make the size of the grid openings comparable with the thickness of the Langmuir layers. However, the size of the grid openings cannot be reduced below a certain level because of:

(a) Mechanical reasons, viz., the mechanical strength of the grid;

2

(b) Thermal conduction considerations, that is, if the grid wires are too thin, thermal conduction becomes worse and this may cause grid emission; and

(c) The tube drop, see, for example page 1357, Fig. 12, which may increase too much if the grid openings become too small.

It can be readily seen from the above formula that the only way to reduce the effective grid transparency is to increase the value of the term *U* in the formula. This expression increases on the one hand with increasing negative grid bias *V_g*, and on the other hand with an increase in the expression under the root sign. An increase of the negative grid bias, that is, the interruption or cutoff voltage, leads to increased power requirements for extinguishing or interrupting the discharge of the tacitron and thus to a decrease of the total efficiency. Therefore, the only practical way is to increase the value of the expression under the root sign. This expression increases if *M* the ion mass is increased, because the ratio *T_e/T_p*, i.e. the ratio of the electron and ion temperatures increases simultaneously, see Knoll, Ollendorf, Rompe "Gasentladungstabellen" published by Julius Springer, 1935, Berlin, p. 99. In accordance with this theory gases with the highest atomic weight should be used in tacitrons. In fact, all known tacitrons now generally use an xenon filling, or a filling of mercury vapour.

In comparison with conventional thyratrons, tacitrons have many advantages. For example: The discharge 30 may be extinguished or interrupted by a negative grid bias; their noise is negligible; and their application is not limited by the time required for deionization of the gas filling. The disadvantage of existing tacitrons with xenon or another heavy noble gas filling resides in the 35 fact that the current or power which may be controlled by a tacitron, the size of which is comparable with the size of a conventional thyratron, is considerably smaller, because, in the case of greater anode currents, the proper mode of the discharge is not preserved and the tacitron 40 cannot be extinguished by application of a grid bias. Furthermore, tacitrons filled with noble gases cannot be used for higher voltages (in the order of kv.), as will be discussed later.

The object of this invention is to provide a tacitron 45 which is free of the above mentioned disadvantages of tacitrons filled with xenon or other noble gases, while retaining all of the advantages of existing tacitrons. The invention is characterized by the use of a hydrogen filling in tacitrons. Contrary to all expectations from 50 existing theories and conclusions drawn from previous experience, it has been quite unexpectedly proved by new experiments that, by using hydrogen which is the lightest known gas, it is possible to achieve better results, to increase considerably the controlled power output and to 55 decrease the necessary control power. Experiments have been carried out to compare the properties of the same system using first a xenon filling, and secondly a hydrogen filling. With the xenon filling a power of up to 60 w. 60 could be extinguished or interrupted by means of the grid bias; while, with the hydrogen filling it was possible to switch off a power of 1 kw. by means of the grid bias; and, in pulse operation, as much as 15 kw. could be controlled. Thus the power controlled by the hydrogen 65 filled tacitron was 15 to 200 times larger than the power controlled with the tacitron having the usual xenon filling.

For a more detailed comparison of tacitrons with xenon and hydrogen fillings, some characteristics are shown in the accompanying drawing, wherein: Fig. 1 70 shows the so called cutoff characteristics, Fig. 2 shows the maximum controlled voltage and tube-drop as a function of the filling pressure, and Fig. 3 is an axial section-

al view of a typical tacitron which is filled with hydrogen in accordance with the present invention.

Referring to Fig. 3 in detail, it will be seen that a tacitron, to which the present invention relates, includes a sealed glass envelope 2 mounted on a base 12 and having a sealed tube 11 at its lower end through which hydrogen is pumped into the envelope during manufacture. The envelope 2 contains an upper ceramic insulator 3 and a lower ceramic insulator 8, and a central oxide cathode 4 extends between, and is supported by, the upper insulator 3 and a mica cathode holder 7. A grid 5, formed, for example, of a fine wire mesh or network, extends around cathode 4 between insulator 3 and a grid carrier 10, and an anode 6 surrounds grid 5 and is connected to an anode lead 1 which enters the envelope 2 at the top of the latter. The base 12 has the usual prongs extending therefrom for reception in a corresponding female receptacle, and leads 9 extend from such prongs into the interior of envelope 2 and there connect to the cathode and grid.

In existing tacitrons having the above briefly described structure, the envelope 2 is filled with a noble gas, for example, xenon or mercury vapour, but, in accordance with the present invention, the envelope 2 is filled with hydrogen which replaces the usual noble gas, as previously mentioned. The cutoff characteristics shown in Fig. 1, present the dependence of the maximum controlled source voltage V_a on the extinguishing grid bias V_g with different anode currents I_a . From these characteristics it is possible to deduce the negative grid bias required for interrupting the anode current at a certain source voltage. It can be seen for example that in the case of a xenon filling a 100 ma. current with a source voltage of 400 v. may be interrupted by a negative grid bias of 15 v., while with a hydrogen filling a negative grid bias of only 3.5 v. is required under the same conditions. With a xenon filling it is not possible to interrupt currents larger than 200 ma., while with a hydrogen filling it is even possible to interrupt a current of 1 a. with a source voltage higher than 1 kv.

In Fig. 2 the unbroken curves present the dependence of the tube drop on the filling gas pressure. It can be seen from these curves that tacitrons filled with xenon (or other noble gases) cannot be used for controlling a higher voltage. This would require a decrease of the filling pressure, but the tube drop V_o would be increased simultaneously. The tube drop may not exceed the so called destructive voltage, which means a tube drop, where a destruction of the oxide cathode sets in by ion bombardment. The destructive voltage in the case of noble gases and mercury vapour is about 20 v., while with hydrogen it has a value of about 600 v. Fig. 2 shows that the applicable minimum pressure for xenon is about 5×10^{-2} mm. Hg or torr, which corresponds to a tube drop of 18 v. and a maximum controlled voltage V_a of 2 kv. With hydrogen the tube drop has a

value far below the value of the destructive voltage, even at a pressure of 3×10^{-1} mm. Hg or torr, which corresponds to a maximum controlled voltage of 10 kv. It is evident that the results achieved with a hydrogen filling differ very favourably from the results achieved with a xenon filling. The results are still very favourable even if the hydrogen filling contains a certain amount of other gases.

Hydrogen has also a good effect on the emission of the oxide cathode. The use of a hydrogen filling enables the construction of tacitrons as large as a conventional thyratron for a similar output power; with a hydrogen filling it is also possible to design tacitrons for very high output powers in the order of tens of kv. Such power outputs could not be achieved with existing tacitrons filled with xenon or other noble gases.

What I claim is:

1. In combination in a gaseous discharge device of the tacitron type, an envelope having therein a cathode electrode, an anode electrode spaced from said cathode electrode, an apertured grid electrode positioned intermediate said cathode and plate electrodes, and a filling of hydrogen, said grid electrode being adapted to interrupt current flow between said cathode and plate electrodes by closing the apertures of said grid electrode by a space-charge sheath which is opaque to electrons attempting to move from said cathode electrode to said anode electrode, the maximum dimensions of the apertures of said grid electrode being substantially equal to the thickness of said space-charge sheath.
2. In combination in a tacitron, an envelope having therein a cathode electrode, an anode electrode, an apertured grid electrode positioned between said cathode and anode electrodes for interrupting current flow between said cathode and anode electrodes by causing the formation in the envelope of Langmuir layers, and a hydrogen gas filling, the dimensions of the apertures of said grid electrode being comparable to the thickness of said layers.
3. A combination as in claim 2, wherein the pressure of said hydrogen gas filling is at least 3×10^{-1} millimeters of mercury.
